UNITED STATES PATENT OFFICE.

HEZEKIAH CONANT, OF WILLIMANTIC, CONNECTICUT.

MACHINE FOR WINDING THREAD ON SPOOLS.

Specification of Letters Patent No. 26,415, dated December 18, 1859.

To all whom it may concern:

Be it known that I, HEZEKIAH CONANT, at present residing at Willimantic, in the county of Windham and State of Connecticut, have invented certain new and useful Improvements in Apparatus for Winding Thread of Cotton, Silk, Linen, or other Fibrous Material Upon Bobbins or Spools, and that the following specification, taken 10 in connection with the drawings, is a full, clear, and exact description thereof.

In the drawings on Sheet No. 1, Figure 1 is an elevation of the machine taken from the front end thereof or that on which the 15 bobbin is mounted. Fig. 2 is a top view or plan of the machine. Fig. 3 is a side elevation of a pattern cam or traverse changer. Fig. 4 is an end elevation of the same. Fig. 5 is a development of this cam or traverse 20 changer upon a plane. Fig. 6 is a detail drawing in section of the cam and lips upon which it acts to change the traverse or 25 direction of winding of the thread upon the spool or bobbin. Fig. 7 is an elevation in detail of the rigger socket and latch, and in Sheet No. 2, Fig. 1, 2, and 3 are respectively a plan, an end elevation, and a side elevation of a modification of apparatus for 30 stopping the action of the machine when the spool is full.

This machine is specially contrived for winding thread upon ordinary spools, the ends of which are conical or irregularly conical, so that the layers or courses of thread 35 wound thereon are of necessity each longer than the other as the outside of the spool is approached; but it will also be useful in winding spools whose ends are perpendicular to the axis of the spool and on which all the 40 layers of the thread are consequently of the same length.

And the object of my invention is to wind thread upon spools with regularity and precision, layer upon layer, and each filling the 45 whole length of the spool, without any attention on the part of the operator further than to remove and replace spools to cut the thread and fasten it when the spool is full, and to attach the thread to a fresh spool, 50 and set the machine in motion.

And to this end the nature of the first part of my invention consists in combining a pattern cam or traverse changer with nuts, and right and left hand screws or their 55 equivalents for the purpose, the operation of the combination being such that a thread

guide shall have its motion reversed and its length or distance of motion regulated automatically, substantially in the manner and for the purpose herein specified. 60

And the nature of the second part of my invention consists in constructing a pattern cam or traverse changer with a series of steps or projections or their equivalents which come into action successively; each 65 one of the series being of such proportionate length compared with the others that the change of motion of the thread guide shall take place when any layer of thread completely fills the bobbin. 70

And the nature of the third part of my invention consists in combining with a pattern cam and right and left hand screws and traversing nuts, a stop motion substantially such as is hereafter specified so that the 75 whole apparatus shall be brought to rest when the bobbin is completely filled.

And the nature of the fourth part of my invention consists in making the lips of the 80 levers that actuate the screw nuts or their equivalents for the purpose they serve, adjustable, so that different lengths of spools may be wound properly by the same traverse changer.

And the nature of the fifth part of my 85 invention consists in mounting the presser and thread-guide directly upon the traverse rod, whereby the machine is cheapened and moves more steadily and accurately.

And the nature of the sixth part of my 90 invention consists in a tension and stop motion lever, in combination with a presser guide and spooling machine, the operation being to deliver the thread under proper tension to the guide and presser and to stop the 95 whole apparatus automatically when the thread breaks or is entirely wound off of the large bobbin from which thread is supplied to the apparatus.

My machine is in many respects similar 100 to machines now in common use for winding sewing thread, cotton or silk upon spools, such machines being however hand machines or machines in which the operator causes the change or direction of motion of the thread 105 guide; determines when that change shall take place and stops the apparatus when a bobbin is filled or the thread breaks; and as far as my machine is like such machines my 110 description will be succinct as the latter are well known to those skilled in the art of constructing machines for spooling thread.

My machine consists of a bed plate such as shown in the drawings with two end pieces or uprights attached thereto, and in these in proper boxes are mounted a shaft A which 5 supports the spool on which thread is to be wound, a shaft B, carrying a right and left hand screw, such as l and r ; and a traverse rod C.

The shaft A is provided with a pulley 10 such as a' , to receive a belt which gives motion to the whole apparatus; with a conical pulley such as a^2 and with a socket into which a spindle is inserted upon which the spool to be wound is forced and by which it 15 is supported; and below this shaft lies a rod, to which is attached a link p , to which is connected a hand lever R and on the end of the rod are two projections o o , the whole being for the purpose of removing and 20 placing spools, and being like the shaft and its pulleys, the same or nearly the same as those in ordinary use in spooling machines.

The shaft B with its conical pulley b' and right and left hand screws is like those in 25 ordinary use and is driven by a band like b , the use of the conical pulleys being to make the same screws serviceable for thread of different numbers and consequently diameters, by altering the relative velocity of the 30 screw shaft and that which supports and revolves the spool. The traverse rod is so mounted as to have a sliding motion in the direction of its length only, and directly upon the end of this rod is a guide and 35 presser D identical in construction with those now in actual use, there being an adjustable spiral spring to bear the guide proper, as at D^2 , down upon the thread being wound and a handle to relieve the pressure 40 when a spool is to be replaced or removed. This presser and guide as a whole is, in machines now in use, connected to the traverse rod by a jointed connection but not attached directly to it as in my machine, 45 and this direct attachment is important as the presser is thereby caused to follow all the motions of the traverse rod with perfect precision without any backlashing, or pause while the traverse rod is changing from a 50 motion in one direction to the reverse thereof.

The traverse rod in order to wind thread properly layer upon layer must cease moving in one direction and instantly commence 55 moving the reverse way as soon as one layer of thread fills the spool completely from end to end, and on ordinary spools the distance through which it moves must vary as each course of thread is wound. In order 60 to effect this operation I have mounted upon the traverse rod on proper pivots or hinges, two levers or swinging bars E, E, the one carrying the section of a right hand, and the other of a left hand nut corresponding 65 with the screws on shaft B. These bars are

mounted by means of adjustable points or pivots with set screws as shown in the drawings so that they may fall and rise freely and so that when moved horizontally they may force the traverse rod to follow their 70 motions instantaneously without backlash or endplay. If one of these levers were raised (while the machine was in motion) so that its nut came in gear with one of the screws the traverse rod would move in one direction, when that nut was dropped so as to release itself from the screw, the traverse rod would cease to move, and when the other nut was lifted the traverse rod would move in the opposite direction. In order to accomplish this alternate dropping and lifting of 75 the levers automatically I have mounted upon the shaft B a pattern cam or traverse changer such as G which is bored out so as to turn freely upon the shaft. When this 80 cam is slipped on the shaft one end rests against a stationary hub, and set and pinch nuts such as k k are brought to bear against a disk of cork or leather inserted in a recess turned out in the other end; the object of 85 the arrangement being that the cam shall be moved by friction as fast as the shaft moves, when unlocked or permitted to turn, but may be locked fast and not moved at all while the shaft revolves at full speed inside 90 of it. From the periphery of this cam stand out a number of steps or prejections as plainly shown in the drawing on the end of each swinging bar or drop lever E, is formed a lip F, or these lips may be separate pieces 95 100 and secured in place by set screws as shown in the drawings; these lips are sufficiently thin (see Fig. 6,) to slide freely between the steps or prejections on the traverse changer, and are so mounted on the swinging bars 105 that they will engage with the prejections. Each bar may be prevented from dropping below a certain line by a stop such as k' , and its lowest position should be such that the nuts which it controls shall be out of 110 contact with its corresponding screw thread.

Now the operation of these parts is as follows: Suppose that the lip F' is in its highest position resting on one of the prejections, and the machine in motion, then the 115 nut pertaining to F' will be in gear with the screw r , and the lip and the traverse bar will be moving toward the conical pulleys or rear of the machine; at the same time the lip F² will be resting upon the step or prejection next lowermost with its nut out of gear and will follow the motions of the traverse rod; as soon as the end of the lip F' slips off of the step or prejection on which it rested, the nut that it governs will drop 120 out of contact with the screw thread, the motion of the traverse bar will cease and the traverse changer being unlocked will commence to revolve by its friction connection 125 with the shaft, as it revolves, it will almost 130

instantaneously lift up the lip F^2 so that the nut governed by it comes into gear, when the traverse rod will commence to move in the opposite direction. The traverse changer 5 is locked fast again by the lip as soon as the nut engages with the screw and while F^2 was rising, F' dropped onto its stop or on to the next projection below, and as soon as F^2 commenced moving toward the front of the 10 machine F' followed it, entering the same space between two projections but with its nut out of contact with the screw as that nut lies at a greater distance below its controlling lip than the nut governed by F^2 lies 15 below F^2 ; that is to say, when both lips are in the same space between two projections, the nut on F^2 may be in gear with one of the screws, while the nut pertaining to F' is just out of gear with the other.

20 The traverse rod continues to move toward the front of the machine until lip F^2 drops off the end of the projection or step on the traverse changer which is then unlocked and lifts F' so as to put its nut in gear while 25 the nut of F^2 itself falls out of gear with the screw. The traverse rod therefore again commences to move toward the rear of the machine and so continues to do until the lip F' again falls off of the projection which 30 held it up. The office of the cam therefore is to permit one nut to drop out or be released from gear and to throw the other nut into gear when each successive layer of 35 thread is completed and its shape and motion may be variously modified so long as it produces such effects automatically; it may moreover be mounted upon a shaft other than that carrying the screws, if thought desirable, and may be caused at times to rest and at others to move rapidly in many 40 ways known to mechanics, so long as it acts to govern the motion of nuts or their equivalents substantially in the manner specified.

45 Spools on which sewing thread or cotton is wound are generally turned with conical heads or ends, each layer of thread is therefore longer than the one below it and each traverse of the traverse rod must be of greater length than the one preceding it; 50 each lip therefore must hold the nut it governs, in gear for a longer time as each successive layer of thread is wound and each step or projection on the traverse changer is therefore made longer than the one which it 55 follows as the cylinder revolves, as clearly shown in the drawings especially in Fig. 5, and the relative length of the steps must be governed by the shape of the heads of the spools. The thread may be wound so as to 60 fill spools of any shape by a proper change of length of the projections, the longest of which must be as much longer than the shortest as the outermost layer of thread is longer than the inmost or first course or 65 layer.

The lips as before stated are in the best form of the machine adjustable so that they may be brought toward and separated from each other; when separated they will cause their respective nuts to remain less time in 70 contact or engagement with the screws, when brought together, the opposite effect takes place; spools of different lengths may therefore be wound accurately with the same 75 traverse changes.

It is important that the winding should be stopped at the instant that the spool is filled and the last course completed, first, for the reason that the latter will then present a smooth surface, from end to end of 80 the spool; second, because the machine will then have all parts in the right position to commence winding another spool; and for this purpose I have contrived a stop motion, two modifications of which I will describe. The first is shown on the first sheet of drawings. A rigger or shipper X is fitted so as to slide freely in the frame of the machine and is drawn backward by a weight or spring, and when in its rearmost position 85 it holds the driving band on a loose pulley, or in other well known way stops the machine; when drawn forward by hand, it moves the band off of a loose pulley so as to put the machine in motion and is held in 90 that position by a latch L , dropping into a socket on an arm depending from the rigger. If the latch be lifted the spring or weight will draw the rigger backward and stop the machine. The latch L , is pivoted 100 at L' and has attached to it an upright link (clearly shown in Fig. 1) to which is connected one arm of a bent lever; the other arm of this lever rises vertically alongside of that end of the traverse changer nearest 105 the nuts k k , and from this end of the traverse changer projects a small pin n , see Figs. 3 and 4. When this pin in the revolution of the machine strikes the upper end of the bent lever, the latch is lifted from the 110 socket, the rigger is drawn backward by its spring and the machine stops.

The pin is so located on the cam that the latch will be lifted at the periods when one of the lips drops off of the last projection 115 and the machine would if not prevented run for a short time by its own momentum after the belt was thrown off, thus commencing a new layer or course of thread. To prevent this I have divided the last and longest projection (see Figs. 3 and 5) at o and moved a short portion of it farther around the pattern cylinder or traverse changer. By this means the belt will be thrown off when the lip drops onto the short piece o and the lip 120 will ride on that short piece thus causing the outer layer of thread to be wound until the machine loses its momentum and stops.

I have by trial regulated the length of the 125 short piece or step of the last projection so 130

as to insure this effect and a length such as shown in the drawings will be effective in machines made after the drawings which are on a scale of 9 inches to the foot.

- 5 Another modification of this same contrivance is shown on Sheet 2nd. A bell crank is there represented as pivoted on the bed plate of the machine and by means of a lever *u* acting on the link of the latch lever 10 *L* before referred to. When the bell crank is moved in direction of the arrow Fig. 3 the latch will be lifted and the machine thrown out of gear. The upper end of the bell crank lever is a spring tending to bear 15 in the direction of the arrow, Fig. 2, against the hub, and the pin *n* as it comes around moves the upper end of the bell crank away from the shaft and into the path of one of the lips *F'* so that when that lip strikes the 20 upper end of the crank it will lift the latch and when it has thrown the crank arm to its limit of motion the arm will pass the end of the pin *n* and fly back against the hub, thus removing itself from the path of the lip and 25 permitting the latter to drop on the next step of the traverse changer as it ought to do.

The position of the arm *m* should be so adjusted with reference to the lip that the 30 belt shall be thrown off so long before the last course of thread is wound that the machine will run by momentum just long enough to complete that course.

In both the modifications of the stop motion the parts return to their proper position in readiness to latch the rigger fast, when pulled into place to start the machine, by the counterbalancing of the levers, or by the use of springs.

40 In case the thread that is being wound breaks or that all the thread is wound off of the supplying bobbin, it is important that the machine should stop at once so that the spool shall not make a turn without thread 45 being wound upon it; if the contrary should happen one layer, and consequently all above it will be irregular unless the machine be run backward to the place at which thread was last wound upon the spool. It 50 is also important that the thread should be delivered to the presser guide under a constant tension so as to insure regularity of work. Having these objects in view I have combined with the winding apparatus a stop 55 lever and tension apparatus shown clearly in Figs. 1 and 2. A standard or arm *m* is fitted somewhere between the supplying bobbin and the presser guide and carries pins such as 1, 3, and 5 and on one of the end 60 plates of the machine or in any other convenient place is pivoted a lever *P*, provided at its free end with pins such as 2 and 4. This lever or a projection from it lies directly above the upright link of the latch lever *L*, in such manner that when the free

end of *P* is not held up, it will fall upon the link and by its weight lift the latch out of its socket and stop the machine.

The thread represented in the drawings by a red line passes from the supply bobbin 70 over a pin on the arm, under a pin on the lever, and so on in succession to the notch in the presser and thread guide, and when the machine is started the drag on the thread will hold up the free end of the lever, but 75 when the thread breaks anywhere between the supplying bobbin and the spool on which thread is being wound the lever will drop and the machine will stop. The weight of the lever will produce a certain amount 80 of tension upon the thread, and the degree of tension can be varied by changing the position of a shifting weight such as that shown at *W* in the drawings.

The form, position, and relative arrangement of parts in this machine may be varied without departing from the principles of my invention, so long as they have the same mode of operation by which the same results are obtained, and any stop-motion may be 90 used in place of those described so long as so combined with a pattern cam or traverse changer as to cause the motion to cease, when that cam has properly directed the filling of a spool by winding thereon successive 95 layers of thread. The precise kind of tension employed is moreover immaterial so long as so combined with a stopping lever that the breaking of a thread shall cause the lever to stop the machine.

Having thus described my improvements in machinery for winding thread I would state that I do not claim, a shaft fitted with right and left hand screw threads, and combined with nuts which may be so shifted by 100 the hand of an attendant that they are alternately in gear with the screws, and while in gear cause a thread guide and presser to move in a direction dependent upon the screw that is acting upon a nut. But 105

I do claim as of my own invention.

1. The combination substantially in the manner hereinbefore set forth of a traverse changer, with right and left hand screws, and with nuts which are alternately in gear 115 with such screws, the combination operating as a whole substantially in the manner and for the purpose herein described.

2. I claim a traverse changer provided with successive steps or teeth substantially 120 such as is before described and acting upon lips as hereinbefore set forth.

3. I claim a stop motion substantially such as is described herein for causing the machine to come to rest when a spool is filled 125 in combination with automatic apparatus substantially such as set forth for regulating the length of motion and change of direction of motion of a guide through which thread is delivered on to a bobbin or spool.

4. I claim adjustable lips substantially such as set forth in combination with a traverse changer whereby spools of different lengths may be wound by the use of the 5 same traverse changer.

5. I claim mounting the presser and thread guide directly upon, or attaching it firmly to the traverse rod, as hereinbefore described, whereby the machine is cheapened and performs its work more accurately. 10

6. And lastly, in combination with apparatus substantially such as described for governing automatically the motions of a

thread guide I claim a tension apparatus and stop motion which arrests the motion 15 of a machine when a thread breaks, substantially by the mode of operation set forth.

In testimony whereof I have hereunto subscribed my name in the town and county of Windham on this 11th day of April A. D. 20 1859.

HEZEKIAH CONANT.

In presence of—

J. R. ARNOLD,
Wm. W. ARNOLD.
